UNITED STATES PATENT OFFICE

2,062,559

APPARATUS FOR REDUCING METAL STOCK

James R. Coe, Watertown, Conn., assignor to The American Brass Company, Waterbury, Conn., a corporation of Connecticut

Application August 29, 1934, Serial No. 741,887

25 Claims. (Cl. 80—14)

This invention relates to apparatus for reducing metal stock and has for an object the provision of improvements in this art.

More particularly the invention relates to reducing apparatus of the step-by-step intermittently acting type and aims to provide improved supporting means for the stock reducing devices; to provide improved means for rotating the stock; to provide improved means for turning a mandrel when used for supporting tubular stock; to provide improved means for feeding stock to the reducing devices; to provide improved means for holding the mandrel in position; to provide means for receiving and reducing tubular blanks of any desired length; and in other respects to advance the state of the art.

In certain known reducing machines of the step-by-step type the reducing rolls are mounted in a reciprocating frame. The frame is made heavy of necessity in order to obtain strength to resist the large strains imposed upon it by the rolls when working on the stock. The known machines as well as the present machine are intended to be used principally for reducing metal in a cold state and this maximizes the strains imposed upon the rockers and frame. The inertia of such heavy frames is correspondingly great and the strains imposed upon the machine as the frame reverses its motion at the ends of its stroke tend to injure the machine and reduce its period of usefulness. According to the present invention the use of a heavy reciprocating frame is avoided by mounting the rolls in a light reciprocating frame and backing the rolls by trackways or backing plates which are mounted in a heavy fixed frame. In this way the required strength and weight are transferred from the reciprocating elements of the machine to the fixed elements. In the present application this type of construction is specifically applied to a machine having rolls with working surfaces which are eccentric to the axes of rotation of the rolls.

In certain known machines of the step-by-step type provision has been made for the introduction of stock into the rear end of the machine, commonly over the rear end of a mandrel which is approximately fixed in its axial position with respect to the reducing devices, and for the delivery of the finished stock from the front end of the machine, whereby the lengths of stock may be fed end-to-end in continuous succession through the machine. Several of the features of the present invention contribute as a group to the through-feed of the stock in the machine. For example, the stock turning mechanism is designed

to permit the stock to move past it without obstruction or manual intervention while continuously engaging the stock for turning it so long as stock is present thereat; the mandrel turning mechanism is designed to permit the stock to move past it without obstruction or manual intervention and to automatically re-engage the mandrel when the stock has moved by; the mandrel and stock guiding devices are designed to permit the stock to move past them automatically; the mandrel holding devices are designed to be disengaged from and engaged with the mandrel very quickly; and the stock feeding devices are designed to permit stock to pass therethrough without obstruction.

The present apparatus is also designed to handle stock of various lengths. Recently there has been a demand for thin-walled seamless tubing of considerable lengths, often upwards of eight hundred to a thousand feet. This has not been obtainable in continuous lengths and attempts have been made to weld shorter sections together. But it is extremely difficult to weld together very thin walled tubing, required for example in the refrigeration art; and when welded, the joints cannot consistently be depended upon. If the joints are bad they are likely to permit the escape of injurious gases. According to the present process it is possible to effect a great reduction, say in the order of four to one and greater, at one pass through the rolls, consequently the starting stock to be handled is not as long as with other processes which effect smaller reductions. Beyond this advantage of machines of this type in general, the present machine embodies a particularly advantageous combination of elements which provide for the handling of very great lengths of original stock.

One embodiment of the invention which exemplifies the above objects and advantages will now be described by reference to the accompanying drawings wherein:

Fig. 1, including the parts 1a and 1b, is a side elevation of a complete machine embodying the present invention;

Fig. 2, including the parts 2a and 2b, is a corresponding plan view;

Fig. 3, including the parts 3a and 3b, is a corresponding central vertical section taken approximately on the line 3—3 of Fig. 2;

Fig. 4 is an enlarged plan view of the head end, i. e. the reducing end, of the machine shown at the right of Fig. 2b with some of the upper parts removed;

35 Fig. 19 is a transverse vertical section taken on the line 19—19 of Fig. 18.

In the machine selected to illustrate the invention, as shown from right to left in the assembly views 1 to 3, there is provided: A, means 40 for turning the finished stock; B, the reducing rolls and the mounting means therefor; C, means for clamping the stock; D, the main driving mechanism; E, guide mechanism for the stock and mandrel; F, mechanism for turning and feeding the stock; G, power mechanism for operating the stock feeding mechanism; H, mechanism for turning the mandrel; I, mechanism for holding the mandrel; and J, auxiliary mechanism for holding extensions of the mandrel for handling 50 greater lengths of stock.

The various parts of the machine are operatively supported by a main frame 20 which may be formed and assembled in any convenient manner, the front portion 20a which carries the reducing rolls and driving mechanism being relatively massive to take the heavy strains imposed upon it, the middle portion 20b being in the general form of an elongated box for supporting the long mandrel and stock, and the rear portion being principally formed of a long power cylinder 20c which will later be discussed. The middle and rear portions are supported as required by appropriate supports or legs 20d.

60 A motor M (Fig. 2b) furnishes the principal power for operating the machine. The motor shaft 22 acts through a flexible coupling 23, a gear shaft 24 and suitable worm gearing housed within a gear casing 25 to drive a jack shaft 26. The jack shaft through gears 27, 28 (Fig. 3b) drives a crank shaft 29. The crank shaft 29 through crank pins 30 and connecting rods 31 drives a roll frame 32. At its rear end the roll frame is guided by rollers 34 (Fig. 5) rotatably mounted thereon, which rollers operate between 75 longitudinal guides 35.

The reducing devices

In the front portion of the frame there are carried a set of eccentric-grooved reducing rolls 36 and backing rolls 37. The backing rolls operate against backing plates 38 secured in the main frame 20. The working stresses from the reducing rolls are thus transmitted directly into the main frame 20 which permits the roll frame 32 to be made very light thus minimizing the stresses caused by its reciprocation. The roll frame (Figs. 4 and 7) is provided with upper and lower blocks 40 and front straps 41 which are held by bolts 42. The backing rolls are mounted in bearings in these blocks 40 and the reducing rolls are mounted in independent bearing blocks 43 which are slidable in the frame. The reducing rolls are provided with concentric extensions 44 which roll against the backing rolls 37. The reducing rolls are held in position by the backing rolls 37 between which they fit at their circumferences. 10 The reducing rolls are provided with gears 46 which mesh with gears 47 on the backing rolls and these in turn mesh with fixed racks 48 secured to the main frame 20. The gears of the opposed reducing rolls, however, are not in mesh with each other. 15

As seen in Fig. 7 there is a backing roll on each side of the reducing rolls. These axially aligned backing rolls may be placed on a common shaft but as shown in the drawings they are mounted on separate short shafts so as to leave a space between them for the passage of cooling or lubricating fluid to the reducing rolls. An upper housing 50 and a lower housing 51 are provided for confining the fluid thus employed. The front and rear plates of these housings are shown in Fig. 5. The plates are provided with aligned openings for receiving the mandrel and stock. Fig. 5 also shows the means provided for supplying the fluid, the means hereby employed comprising a telescopic pipe 52 carried by the frame, which slides in a packed joint in the end of a fixed fluid supply chamber 53. The pipe 52 has openings in its lower side within the housing 50 for the outflow of fluid to the rolls. Fluid is supplied to the chamber 53 by a supply pipe 54. The used fluid is caught in a trough 55 and carried off by a drain pipe 56.

The rolls may be adjusted from and toward each other by any suitable means. As shown in Fig. 5, one or both of the members carrying backing plates 38 may be mounted on an inclined surface 57 and be moved and held by oppositely acting adjusting screws 58, 59 acting against proper anchorages. Since only small adjustment is ordinarily required adjustment for only one side has been shown herein. 50

Stock holding means

When feeding in a new length of stock or when returning the stock feeding device to its rearward position it may be desirable to hold the old length of stock, i. e. the one which has been partly reduced, in a fixed longitudinal position. For this purpose, as shown at C in Figs. 3b and 5, there is provided a clamp 61 operated in properly timed manner by hand or by means coordinated with the other parts of the machine. Herein the clamp is operated by a piston 62 movable in a cylinder 63. The cylinder is served by a pipe 64. The piston and clamp are raised by a spring 65. 60

Driving mechanism for stock and mandrel turning devices

In order that the rolls may work effectively on different parts of the circumference of the 75

stock, means are provided for turning the stock at times. This may be accomplished by acting directly upon the stock, either before or after reduction, or by acting upon the mandrel. Turning means of all of these types are disclosed herein, it being thought that the machine will function more effectively if the several types are used concurrently, although the machine will function with any one alone. At this point the driving mechanism for operating all of the turning mechanisms will be described.

Referring to Figs. 2b and 15, the shaft 22 of motor M, through a gear train housed within a gear casing 67 drives a cam shaft 68. A cam 69 of the desired configuration acts upon a cam roller 70 and through it operates a transverse bar 71 slidably in suitable guides. The bar is moved in the opposite direction by a piston 72 operating within a cylinder 73. Motive fluid may be served to the cylinder by way of a pipe 74. Fluid pressure may be kept constantly upon the piston 72 so as to keep the roller 70 constantly pressed against the cam 69. The cam thus times the operation of the turning mechanism. By making the receding portion of the cam surface abrupt the turning action may be made almost instantaneous so as to accomplish the turning movement while the reducing rolls are reversing their direction of travel at the ends of their stroke even when the machine is operating very rapidly.

The bar 71 carries a pawl 75 which actuates a ratchet wheel 76 fast on a gear wheel 77. The gear wheel 77 drives a gear 78 and through it the longitudinal turning shaft 79.

35 Through suitable bevel gearing (Fig. 3b) 80, 81 the shaft 19 drives a short vertical shaft 82. The ratio of these gears determines the angle through which the stock is turned at each stroke. Usually the stock is turned from 60° to 90°. The shaft 40 82 through bevel gears 83, 84 drives a longitudinal shaft 85 extending along the box-like portion 20b of the main frame.

Through similar bevel gears 86, 87, a vertical shaft 88 and bevel gears 89, 90, the shaft 79 drives 45 a hollow shaft 91 mounted in a bearing 92 at the front end of the machine.

Turning mechanism for finished stock

As shown in Fig. 5, the hollow shaft 91 carries a disc 93 which also has an opening at its axis. The openings through the shaft and disc are made large enough to permit the passage of stock therethrough. The disc is provided with a plurality of brackets 94 on which are mounted bell crank levers 95. One arm of each lever carries a grooved wheel 96 for engaging the stock and the other arms of the levers are pulled toward each other by springs 97 so as to press the grooved wheels upon the stock. The wheels may be lined 60 in their grooves with friction material if desired to give them a good grip on the stock.

From the preceding description it will be seen that the disc and the grooved wheels are rotated intermittently as the stock is released from the reducing rolls and by friction with the stock cause it to rotate. It will also be obvious that stock may be pushed in between the grooved rolls in the normal operation of the machine and when so positioned will be firmly engaged due to the resili-
ent action of the springs.

Stock feeding and turning means

The stock feeding means permits the stock to be fed forward continuously from the rear end of the machine. It is also adapted to accommo-

date stock of great length. Hence the feeding means is of the type which grips the stock along its outer circumference. The feeding mechanism is also of the type which will be designated as the "trip feed", that is, the feeding device grips the stock and carries it in successive relatively short steps for a considerable distance and then returns to the starting position to re-engage the stock at a new point along its length. Among the advantages of this type of feeding mechanism are the greater certainty and accuracy of feeding and the less likelihood of injury to the stock at a number of places by reason of the very rapid engagement and disengagement characteristic of the more frequently acting feeding devices. The feeding mechanism herein is also employed for turning the stock. It is shown in Figs. 1a, 2a, 3a, 9, and 10.

Referring to Fig. 10, the stock S is adapted to be gripped on its outer surface by a collet chuck 100 secured in a rotary sleeve 101. The chuck is clamped upon the stock by a collar 102 which is slideable thereon, the collar and chuck being provided with mating inclined surfaces as usual in this type of chuck. The collar is rotatably mounted in an annular bracket 103, bearings 104 being interposed between them, and is secured by a nut 105. The bracket 103 is mounted on a cylinder casting 106 as, for example, by being made integral therewith.

The cylinder 106 is associated with and movable relative to an auxiliary or clamping piston 107 mounted on the front end of a feed plunger 108. Also mounted on the plunger 108 is a frame 109 in which the sleeve 101 is rotatably secured. 35 Bearings 110 facilitate the rotation and a nut 111 secures the parts together. The sleeve 101 is rotated to rotate the chuck and the stock held thereby. For this purpose it is provided with a gear 114 in mesh with a gear 115 secured to a sleeve 116 rotatably mounted in the frame 109. The sleeve is secured in the frame by a nut 117. The sleeve 116 is slidably splined to the longitudinal shaft 85 hereinbefore referred to. 40

Means are provided for opening the chuck 100 when it is not positively gripped upon the stock. As shown in Fig. 9, the bracket 103 is provided with arms 118 and to these arms are attached rods 119 which pass loosely through openings in arms 120 secured to the frame 109. Springs 121 are interposed between the arms 120 and nuts 122 on the rods. The springs thus normally tend to move the collar 102 to the left as viewed in Fig. 10 to release the chuck. The pneumatic device, comprising the cylinder 106 and piston 107 tends to move the collar to the right and engage the chuck with the stock.

Referring to Fig. 3a, the plunger 108 is attached to a piston 125 operating in a long cylinder 128. This cylinder has been referred to as part of the rear portion 20c of the main frame. A stuffing box 127 to prevent leakage is provided where the plunger passes through the end of the cylinder. 60

The means for regulating the motive fluid applied to the feeding piston may be of any suitable type, as for example like that disclosed in my pending application, Serial Number 704,609, filed December 30, 1933. Enough of this will be explained here to furnish an understanding of its action. Air is supplied to and exhausted from one end of the cylinder 126 by a pipe 128 and a four-way valve 129. The valve has an inlet pipe 130, exhaust pipe 131 and a pipe 132 which leads to a reservoir tank 133. The other end of the 75

cylinder is supplied with liquid, such as water or oil, by way of an inlet pipe 134 provided with a check valve 135. Fluid is exhausted from the cylinder 126 by an exhaust pipe 136 and a return pipe 137 leading to the tank. The exhaust of liquid from the cylinder is controlled and timed by a poppet valve 138 operated by a cam 139 on the shaft 79. A needle valve 140 controls the amount of the exhaust and by this the amount of stock feed.

It is desired that the chuck 100 shall grip the stock whenever the feed piston is actuated in feeding direction. For this purpose a by-pass conduit 143 extends through the piston 125, its plunger 108 and the auxiliary piston 107 whereby pneumatic fluid is conducted from the "head" end of the cylinder 126 to the "head" end of the cylinder 106. Fluid may be exhausted from the cylinder 106 by the by-pass conduit, though for quicker relief an exhaust valve 144 may also be employed.

The valves 129 and 144 may be operated either by hand or automatically by the machine.

In operation pneumatic fluid is supplied to the "head" end of the cylinder 126 by the valve 129. At the same time the top of the tank 133 above the liquid is left open to exhaust. It will be presumed that the "plunger" end of the cylinder 126 is filled with fluid, the same being trapped in the cylinder by the valves 135 and 138. The periodic operation of the poppet valve 138 permits a small amount of liquid to be exhausted from the cylinder back into the reservoir tank 133. The liquid is forced out by the action of the pneumatic fluid which constantly urges the piston toward the crank end. After the plunger has moved the stock as far as desired toward the reducing devices the valve 129 is reversed to connect the head end of the cylinder with the exhaust pipe and to connect the top of the tank with the pneumatic fluid source. This will force liquid back into the plunger end of the cylinder and move the piston 125 back to the head end of the cylinder. When pressure is relieved in the cylinder 106 the chuck will release the stock to permit return of the piston 125 and associated parts without causing the stock to be moved back.

When the valve 129 is again reversed to admit pneumatic fluid under pressure to the head end of the cylinder, the fluid will flow back through the by-pass conduit 143 to the cylinder 106. This will move the cylinder out, the piston 107 being fixed on the plunger rod, and carry the collar 102 against the action of the springs 121 up the inclined surface of the chuck 100 to cause the latter to grip the stock. It will continue to grip the stock so long as the feeding action continues or so long as there is fluid under pressure in the head end of the cylinder 126.

60 Stock and mandrel guide means

As the stock feeding chuck moves along it shortens the length of unsupported stock and mandrel ahead of it and increases the length of unsupported stock and mandrel behind it. Means are hereby provided for supporting the mandrel and stock so that only short lengths will be left between supports at any given time. Preferably, and as herein shown such supporting means permits the stock to be passed through it automatically and engages the stock or mandrel automatically.

Figs. 2 and 3 show two guides or supports E in front of the feeding device F and two behind it. The plates on which these four supports are

carried may be referred to by the numerals 147, 148, 149, 150. The two end plates 147, 150 are connected together by longitudinal rods or links 151 and the two intermediate plates 148, 149 are connected together by the rods or links 152.

When the feeding device moves forward it first engages the support 148 and moves it forward toward the support 147. The support 148 through the links 152 also carries the support 149 forward away from the support 150. When the feeding head and the support 148 arrive at the support 147 they then carry it forward with them and this in turn through the links 151 carries the support 150 forward.

On the return movement the feeding head first engages the support 149 to carry it and its companion support 148 rearward; and these parts later engage the support 150 to carry it and its companion support 147 rearward.

It will thus be seen that the space between supports is never permitted to be very long.

The details of the supports are shown in Figs. 18 and 19. Here the plate 148 is shown to be guided in ways 153 along the box-like portion 20b of the frame. To ears 154 on the support plates are hinged the guide members 155. Springs of any desired type press the members 155 toward the stock. As shown, coil springs 156 are secured to arms 157 of the members 155 for urging them toward the stock. The members 155 have arcuate notches 158 at the center for receiving the stock.

It is thus seen that the stock or mandrel can be pushed forward through the guides without obstruction and that the guides will always swing forward automatically to receive it and will resiliently engage either the stock or mandrel.

As shown in Fig. 3a similar guides or supports 161, 162 which are located in fixed positions are provided at certain points where the stock and mandrel are otherwise unsupported for considerable distances.

Mandrel holding means

It is desirable to have means for holding the mandrel against unauthorized longitudinal movement. Such means should provide for the ready feeding in of the stock over the rear end of the mandrel and should provide for a limited "floating" movement of the mandrel. This floating movement refers to a slight backward movement of the mandrel which is induced by the rearward movement of the rolls on the stock. By providing the rearward movement of the mandrel and stock the return movement of the rolls is eased and the action on the mandrel and stock is eased as well. By reference to Fig. 5 it will be seen that the rolls on their return movement roll up the taper of the stock and mandrel and this exerts a rearward force on the stock and mandrel which may be considerable, especially when working stock in the cold state.

After the stock and mandrel have been moved back they are again moved forward automatically by the rolls at the beginning of their ensuing forward movement.

The mandrel holding device is shown in Figs. 1a, 3a, 12, 13, and 14. It comprises opposed jaws 165, 166 slidably mounted in a clamp frame 167. The jaws are provided with annular corrugations 168 adapted to register with mating corrugations of the mandrel m. The jaws are operated rapidly and simultaneously by a handle 169, the shaft 170 of the handle being provided with oppositely

disposed eccentrics 171, 172 cooperating with the eccentric straps 173, 174 of the jaws 165, 166 respectively.

The frame 167 is provided with a base 175 which is slidably mounted in one of the frame supports 20d. It is retained by plates 176 and is limited in its sliding movement by stops 177, 178. A supplementary front stop in alignment with the stock and axis is provided by a bushing 179 and 10 an abutment 180 (see also Fig. 3a). The bushing is retained in the frame 167 by a set screw 181. This provides the "floating" movement of the mandrel referred to above. The bushing and frame and jaws when open provide sufficient 15 clearance for the passage therethrough of the stock.

There may be several mandrel gripping devices as shown in Fig. 3a, any one of which may be operated. The one nearest the reducing devices 20 which can be made effective is the one employed but if the tube stock is so long as to cover the mandrel at such point, a more remote gripping device may be used. For unusually long stock there may be provided supplementary stands or 25 supports 20e which may be secured to the floor of the shop or to any suitable extension of the base frame at any desired distance from the reducing devices. The mandrel *m* may be lengthened correspondingly by the use of one or more supplemental lengths *m*1 and couplings *m*2. Each stand will be equipped with one of the quick-release mandrel gripping devices.

Mandrel turning means

35 In addition to the means already described for turning the finished stock and the stock being fed forward to the reducing devices, it may be desirable to turn the mandrel by direct action thereon. It is also desired that this mandrel 40 turning mechanism shall permit the ready and automatic passage of stock therewith and shall automatically come into operation as soon as the stock has passed.

Such mechanism is illustrated in Figs. 3a, 16 45 and 17, and preferably is placed at several points along the mandrel, as for example near the mandrel gripping mechanisms. Herein it comprises a gear 185 secured in rotative position by a tubular stud 186 which is screwed into the base frame support. The gear is provided with spaced pivot pins 187 upon which are hinged the swinging members 188. The members 188 are provided with forwardly extending arms 189 between 50 which are stretched coil springs 190 for urging the members inward toward the axis of the mandrel and backward toward the gear. The mandrel *m* at this point is provided with a non-circular portion *m*3 adapted to be engaged by the swinging members 188 when stock is not disposed 55 between them. The portion *m*3 is made sufficiently long to permit the floating movement of the mandrel. The gear 185 is driven by a gear 191 on the shaft 85.

60 This mechanism permits the stock to be fed forward automatically, the hinged members 188 readily swinging forward and outward out of the way. After the stock has passed, the hinged members again swing inward to reengage the 65 non-circular portion of the mandrel. The gear 185 is turned intermittently at all times while the machine is in operation so when the members 188 engage the mandrel they will turn it.

65 By providing several turning mechanisms spaced along the length of the mandrel there is

always likely to be one which is free to engage and turn the mandrel.

Operation

The machine will be assumed to be stopped 5 with a previous length of stock almost finished. The machine usually will be stopped when new stock is to be fed in. At this stage, whether the machine is stopped or not, the unfinished length of stock is gripped and held by the clamp C 10 shown in Fig. 3b.

The stock feeding mechanism F (Fig. 3a) is retracted by exhausting pneumatic fluid from the head end of feed cylinder 126 and supplying pneumatic fluid to the top of the reservoir tank 15 133 to force liquid from the bottom of the tank into the plunger end of the feed cylinder 126. When pneumatic fluid is exhausted from the feed cylinder 126 it will simultaneously be exhausted from the auxiliary or clamping cylinder 106 to 20 open the collet chuck 100 and release the stock.

The mandrel clamping devices I and J or such of them as have been in use will be opened to permit stock to be fed in over the rear end of the mandrel. When the stock is pushed forward it 25 swings the hinged members of the mandrel turning devices H and the mandrel and stock guides E out of the way so it may pass. It also moves freely through the feeding chuck and finally stops 30 when it abuts the rear end of the unfinished 35 length of stock. If short lengths of stock are fed a number of them may be introduced at one time. It is only necessary that the stock extend back into the stock gripping chuck wherever that may be located. The stock may be as much longer as 40 desired since the chuck will grip the stock anywhere along its length. If the stock is too long for the main part of the machine the auxiliary mandrel holding device may be erected as far back as necessary. This may render the mandrel 45 turning devices inoperative but will not necessarily disrupt the proper operation of the machine because the stock is usually squeezed down upon the mandrel at the reducing devices so that when the stock is turned the mandrel will be turned also. 50 If it should ever become necessary to turn the mandrel directly when very long stock is being worked it will be a very easy matter to provide turning mechanism on the auxiliary mandrel holding stand. This may be similar in all respects 55 to that already described and may be operated by an extension of the turning shaft 85.

After the stock has been inserted the valve 129 is reversed to supply pneumatic fluid to the head end of the feed cylinder and exhaust the pneumatic fluid from the top of the tank 133. The bypass conduit 143 will simultaneously supply pneumatic fluid to the auxiliary cylinder 106 to cause the chuck to grip the stock. Liquid which is trapped under pressure in the plunger end of the cylinder 126 will be periodically released in small amounts by the cam operated valve 138 to cause the stock to be fed.

The rolls rock back and forth on the stock 65 and perform most of their reduction as they roll forward down the taper of the stock. If the stock is turned when they reach the forward end of their stroke they will consolidate it upon their return stroke.

The turning mechanism A for the finished stock 70 assists at all times in the proper turning but is particularly useful when a length of stock becomes too short to be gripped and turned by the chuck. It has already been explained how this turning 75

mechanism permits the stock to be automatically passed therethrough.

It will thus be seen that the present invention provides improved mechanism for reducing stock, 5 the roll mechanism by reason of its lightness, simplicity and strength, the stock and mandrel turning and feeding mechanism by reason of its simplicity and effectiveness and the readiness with which it permits the passage of stock, the 10 stock and mandrel guide means by its adaptability to easy passage of stock, the mandrel holding mechanism by reason of its quick action and provision for the floating action of the mandrel and the whole combination of apparatus 15 by reason of its unique and practical cooperation and adaptation for the prompt and effective handling of stock even when of unusually great length.

While one embodiment of the invention has 20 been described with some particularity in order to illustrate the principles of the invention it is to be understood that the scope of the invention is not meant to be limited thereby. The true scope of this invention is to be determined by 25 the language of the subjoined claims when read in the light of the above disclosure and the prior art.

I claim:

1. Apparatus for reducing metal stock, comprising in combination, a main frame, opposed parallel backing plates on said frame, a set of reducing rolls provided with eccentric working portions adapted to squeeze increments of length of the stock forward by successive intermittent 30 actions thereon and adjacent concentric portions adapted to cooperate with backing rolls, backing rolls disposed between the concentric portions of the reducing rolls and said backing plates, and means for effecting relative reciprocatory movement between said rolls on the one hand and the backing plates and stock on the other hand.

2. Apparatus for reducing metal stock, comprising in combination, a main frame, opposed 45 parallel backing plates on said frame, a set of reducing rolls provided with eccentric working portions adapted to squeeze increments of length of stock forward by successive intermittent actions thereon and adjacent concentric portions 50 adapted to cooperate with backing rolls, backing rolls disposed between the concentric portions of the reducing rolls and said backing plates, a common frame supporting all of said rolls in proper relative positions for working upon the stock, and means for reciprocating said frame.

3. Apparatus as set forth in claim 2 which further comprises in combination, bearing members for said rolls, which are mounted in said frame so as to be slidable therein in a direction 60 transversely of the axis of the stock.

4. Apparatus as set forth in claim 2 which further comprises in combination, racks secured to said main frame parallel to said backing plates, gears on said backing rolls meshing with said 65 racks, and gears on said reducing rolls meshing with the gears on said backing rolls.

5. Apparatus as set forth in claim 2 which further comprises in combination, means for adjusting one of said backing plates from and to 70 ward the axis of the stock.

6. Apparatus for reducing metal stock comprising in combination, means intermittently acting upon the stock to reduce it, means for intermittently feeding the stock forward, and 75 means for rotating the stock, said rotating means

including members which are resiliently pressed upon the stock at all times while it is positioned between them and which are adapted to be opened into stock-embracing position by the stock itself as it moves forward, a rotatable head for supporting said members, and means for intermittently rotating said head.

7. Apparatus for reducing metal stock, comprising in combination, means intermittently acting upon the stock to reduce it, means for intermittently feeding the stock forward, and means for intermittently rotating the stock, said rotating means including a head through which the stock passes, a plurality of devices hinged to said head and adapted to swing forward when the end of a piece of stock engages them to permit the stock to be passed along between them, resilient means for causing the members constantly to press upon the stock when it is disposed between them, and means for rotating 20 said head.

8. Apparatus as set forth in claim 7, in which said hinged elements open to receive the stock when it is pushed in between them.

9. Apparatus for reducing metal stock, comprising in combination, means intermittently acting upon the stock to reduce it, means for intermittently feeding the stock forward, and means for intermittently rotating the stock, said 30 rotating means comprising frictional elements which are constantly and resiliently pressed against the stock.

10. Apparatus as set forth in claim 9 in which said elements are formed as rollers which roll upon the stock as it is fed forward.

11. Apparatus for reducing tubular metal stock, comprising in combination, a mandrel for supporting the stock, reducing devices intermittently acting upon the stock, means for feeding the stock forward intermittently upon said mandrel, 40 and means for intermittently rotating said mandrel, said rotating means comprising members which are resiliently pressed against a non-circular portion of said mandrel and which are opened by the tubular stock when it is fed in 45 over the rear end of the mandrel to allow the stock to pass, a rotatable head for supporting said devices, and means for intermittently rotating said head.

12. Apparatus as set forth in claim 11 in which 50 said mandrel-engaging members are hinged to said head so as to swing forward when a length of stock is introduced, and springs urging said members toward the mandrel.

13. Apparatus for reducing metal stock, comprising in combination, reducing devices acting intermittently upon the stock, and means for feeding stock intermittently in short increments of length to said reducing devices, said means including a device adapted to grip the stock and 60 through which the stock may pass, a travelling device for moving said gripping device forward without reversal for a plurality of intermittent feeding movements and thereafter returning it to its initial position, and means associated with 65 said travelling device and said gripping device responsive to the application of power to said travelling device to move it forward which energizes said gripping device to cause it to grip the stock to feed it forward, and which is responsive 70 to the withdrawal of forward-moving power from said travelling device for de-energizing said gripping device to cause it to release the stock when moving in a rearward direction.

14. Apparatus for reducing metal stock, com- 75

prising in combination, reducing devices acting intermittently upon the stock, and means for intermittently feeding the stock in short increments of length to said reducing devices and rotating the stock about its longitudinal axis, said means including a device adapted to grip the stock and through which the stock may pass, a head on which said gripping device is mounted, means for rotating said head to turn the stock, a travelling device for moving said gripping device forward without reversal for a plurality of intermittent feeding movements and thereafter returning to its initial position, and means associated with said travelling device and said gripping device responsive to the application of power to said travelling device to move it forward which energizes said gripping device to cause it to grip the stock to feed it forward, and which is responsive to the withdrawal of forward-moving power from said travelling device for de-energizing said gripping device to cause it to release the stock when moving in a rearward direction.

15. Apparatus as set forth in claim 14 which further comprises in combination, means for turning the stock gripping device and thereby to turn the stock in any position of the device in its stock-feeding travel.

16. Apparatus for reducing metal stock, comprising in combination, reducing devices acting intermittently upon the stock, and means for feeding stock forward intermittently in short increments of length to said reducing devices, said means including a chuck for gripping the stock and through which the stock may pass, a fluid cylinder-and-piston device having a travelling part, an auxiliary cylinder-and-piston device mounted on said travelling part, means for simultaneously supplying or exhausting power fluid from both of said cylinder-and-piston devices, and mounting means for said chuck on said travelling part, the chuck and its mounting means being connected, respectively to relatively movable parts of said auxiliary cylinder-and-piston device whereby the stock is gripped when the parts travel in stock feeding direction and is released when they travel in the reverse direction.

17. Apparatus for reducing metal stock, comprising in combination, reducing devices acting intermittently upon the stock, and means for feeding stock forward intermittently in short increments of length to said reducing devices, said means including a cylinder mounted on a fixed frame, a piston mounted therein provided with a tubular piston rod extending through one end of the cylinder, a stock feeding head mounted on the end of said piston rod, an auxiliary piston mounted on said piston rod, a stock-gripping chuck mounted on said head, an auxiliary cylinder slidably mounted on said auxiliary piston, a sleeve member mounted on said auxiliary cylinder embracing said chuck and adapted when operated to cause the chuck to grip the stock, and means to admit pressure fluid to both of said cylinders to operate said pistons simultaneously, whereby the chuck is made to

grip the stock at the beginning of the feeding travel and to continue to grip it throughout the feeding travel.

18. Apparatus as set forth in claim 17 in which said means for admitting pressure fluid comprises a by-pass conduit for conducting pressure fluid from the main cylinder chamber to the auxiliary cylinder chamber.

19. Apparatus as set forth in claim 17 in which said means for admitting pressure fluid comprises a by-pass conduit for conducting pressure fluid from the main cylinder chamber to the auxiliary cylinder chamber, said by-pass including a tubular passage through said piston rod and both of said pistons.

20. Apparatus as set forth in claim 17 in which said chuck is mounted on a rotatable member in said sleeve member and in which means are provided for rotating the rotatable member and chuck to rotate the stock in all positions of the head during the feeding of the stock.

21. Apparatus for reducing tubular stock, comprising in combination, step-by-step reducing devices for acting intermittently upon the stock, a mandrel for supporting said stock between said reducing devices, said mandrel being rotatable about its axis and approximately fixed longitudinally, and means for clamping said mandrel at a plurality of places along its length to accommodate various lengths of stock, the clamping means near said reducing devices being capable of permitting stock to pass when left in inactive condition while a more remote clamping device is used.

22. Apparatus as set forth in claim 21 in which said clamping means comprises an anchorage for a clamping device, which is separate from the remainder of the machine and adapted to be secured at any desired distance from the reducing devices.

23. Apparatus as set forth in claim 21 in which said mandrel is made in sections which may be connected as required to accommodate various lengths of stock.

24. Apparatus as set forth in claim 21 in which all of said clamping means are provided with a limited to-and-fro movement for the purposes described.

25. Apparatus for reducing tubular stock, comprising in combination, reducing devices which roll to and fro on the stock to reduce it, a mandrel for supporting the stock between said reducing devices, and means for holding said mandrel in approximately a given relative position with respect to said reducing devices, said holding means comprising separable members movable in divergent directions adapted to engage circumferential elements on the mandrel between them, an operating shaft for said members, cams on said shaft, means connecting said members with said cams for operation thereby, and means to turn said cam shaft to move said members simultaneously in divergent directions for engaging and disengaging the mandrel.
